UNITED STATES PATENT OFFICE.

JOHN J. RUDDICK, OF WEST NEWTON, MASSACHUSETTS.

TROLLEY SWITCH.

Application filed February 16, 1923. Serial No. 619,497.

This invention relates to trolley switches such as are used in electric signalling systems for trolley cars for the purpose of setting the signal by the movement of the 5 trolley wheel along the trolley wire. The trolley switches which are now commonly used are in the nature of so-called "contacters" that is in the nature of devices that are adapted to be engaged by the trolley wheel 10 as it passes along the trolley wire thereby closing the signalling circuit or circuit of a magnet which in turn controls the signalling circuit. These contacters as heretofore used rely for their operation upon the physical contact of the trolley wheel or trolley 15 harp or some other moving part, with the contacting device in order to give the operative movement to the latter.

In my present invention I have provided 20 a trolley switch in which the circuit is closed by magnetic action solely and this is provided for by employing a circuit-closing device which is magnetically responsive to the magnetic attraction of a body (such as a 25 trolley harp) moving past the circuit-closing device, such magnetic attraction resulting in giving movement to a magnetically-sensitive device to cause the latter to close the circuit. In my invention, therefore, this 30 closing of the circuit is done by magnetic attraction and without any physical contact between the trolley wheel, trolley harp or other moving device and the element to be actuated.

35 In order to give an understanding of the invention I have illustrated in the drawings a selected embodiment thereof which will now be described after which the novel features will be pointed out in the appended 40 claims.

Fig. 1 is a side view of an apparatus embodying my invention, said view showing the side thereof which is adjacent the trolley wire;

45 Fig. 2 is a view of said apparatus illustrating the opposite side;

Figs. 3 and 4 are views showing the manner of connecting the device to and supporting it on a trolley wire;

50 Fig. 5 is a diagrammatic view illustrating the wiring of the device;

Fig. 6 is a fragmentary view showing the housing enclosing and supporting the magnetically-sensitive circuit-closing member;

55 Fig. 7 is a view showing the opposite side of said housing;

Fig. 8 is a top plan view thereof; 60
Fig. 9 is a bottom plan view; 65
Fig. 10 is a section on the line 10-10, 70
Fig. 7; Fig. 11 is a section on the line 11-11, 75

the magnet 6 energized and contacts 3 and
4 in engagement; Fig. 13 is a section on the line 13-13, 85
Fig. 10; Fig. 14 is a fragmentary perspective view 90
of the magnetically-sensitive element and
the contact with which it co-operates; 95
Fig. 15 is a fragmentary sectional view
of the same elements.

As stated above my invention comprehends a magnetically-sensitive circuit-closing member which is responsive to the magnetic attraction of a trolley harp passing adjacent thereto to close a circuit of a relay magnet which when energized operates to close the signalling circuit. 100

In Fig. 5 I have illustrated diagrammatically some of the essential elements of the device and before describing in detail the embodiment of the invention illustrated in Figs. 1 and 2 I will refer briefly to this diagrammatic view. In said Fig. 5, 1 indicates the trolley wire and 2 indicates the signalling circuit. This circuit is normally open and is provided with the two contacts 3 and 4, the contact 4 being carried by the armature 5 of a magnet 6 so that when the magnet 6 is energized and the armature 5 is attracted thereby the contact 4 is closed against the contact 3 thereby closing the signalling circuit 2.

The winding of the magnet 6 is in a normally-open circuit which has therein a magnetically-sensitive circuit-closing member that is adapted to be moved into position to close the circuit by the magnetic attraction of a trolley harp passing along the trolley wire 1. Such a magnetically-sensitive member is illustrated at 7 in Fig. 5 as in the form of a magnetic needle or pin which is suspended from its upper end and the lower end of which is capable of being moved by the magnetic attraction of a trolley harp 87 as it passes along the wire 1 adjacent the member 7.

This member 7 is electrically connected to the trolley wire, such electrical connection 110 being shown diagrammatically at 9 in Fig. 5, and said member 7 co-operates with a con-

tact 8 which is connected to the magnet 6 by a wire connection 10, said magnet being in turn connected to the ground through a wire connection 11, 12. The magnetically-sensitive member 7 normally occupies a position out of engagement with the contact 8 so that under normal conditions the circuit through the magnet 6 is open. The device is so constructed, however, that when a moving body, such as a trolley wheel, passes along the wire 1 in the direction of the arrow there will be a magnetic attraction between the iron trolley harp and the member 7 which will draw the latter into engagement with the contact 8 thereby closing the circuit of the magnet 6 and energizing the latter. As soon as this magnet is energized the signalling circuit 2 is closed at the contacts 3, 4 thus setting the signal.

20 The magnetically-sensitive member 7 is magnetically supported and for this purpose I have provided a magnet comprising two coils 13 and 14 connected by the two bridge pieces or pole members 15 and 27. These 25 coils 13 and 14 are in a shunt circuit leading from the trolley wire 1 to the ground so that they are constantly energized and they, together with the pole pieces 15 and 27 form an electromagnet which holds the 30 needle 7 suspended from the pole piece 15 by magnetic attraction. In the diagram the winding 14 is connected to the trolley through the wire connections 16 and the two windings are connected through the wire 35 connection 17 while the coil 13 is connected to the ground through the wire connections 18 and 12.

Referring now to Figs. 1 and 2 the signal-actuating magnet 6 is shown as supported in 40 a frame 19 which is carried on the bridge piece 15 connecting the two coils 13 and 14, the latter having their lower ends secured to ears 28 extending from a connecting piece 27. The bridge 15, frame 19, coils 13 and 45 14 and connecting member or guide 27 thus constitute a frame or support on which the operative parts of the device are sustained. This frame or support is supported adjacent the trolley wire 1 by some suitable 50 means. In the construction shown the bridge member 15 is provided at its ends with extensions or ears 20 which are secured to spacing arms 21 that extend laterally and in turn are secured to a shoe 22 situated 55 above and connected to the trolley wire 1. The arms 21 are provided with projections 23 which are received in apertures formed in yokes 24, the latter being supported from posts or other supports 25 by means of guy wires 26.

The yokes 24 are provided with set screws 29 which set up against the projections 23 and which serve to hold the frame structure in its proper vertical position. With 60 this construction the supporting frame will

be electrically connected to the trolley wire through the arms 21 and shoes 22.

The current for the windings 13 and 14 of the electromagnet is taken from the trolley wire 1 through the frame and in the construction shown in Figs. 1 and 2 the winding 14 is connected to the frame by a connection 16, the latter being secured to the frame by a binding post 99. The wire connection 18 which connects the winding 13 to the ground is shown in Figs. 1 and 2 as leading to a binding post 98 on a plate 61 which is secured to the insulating block 31, the ground wire 12 being also connected to this plate.

The wire 11 connecting the magnet 6 with the ground is shown in Figs. 1 and 2 as leading from said magnet to the binding post 98 and thus being connected to the ground through the plate 61.

The signal circuit wire 2 leads to a terminal 30 supported on a block 31 of insulating material which is carried by the frame 19.

The contact 3 in the circuit 2 is carried by a swinging arm 91 which is pivoted at 32 on a plate 33 supporting the terminal 30. This arm is normally held against a stop 34 by means of a spring 35. The contact arm 4 is mounted on a swinging arm 36 which is pivoted at 37 to a block 38 carried by the frame 19, said arm 36 supporting the armature 5 for the magnet 6. The stop 34 normally holds the arm 91 separated from the arm 36 so that the contacts 3 and 4 are separated. Since the arm 36 is suspended from the frame 19 which in turn is electrically connected to the trolley wire 1 through the supporting arms 21 it follows that whenever the armature 5 is attracted by the magnet 6 thereby to swing the arm 36 and bring the contact 4 into engagement with the contact 3 a circuit will be established from the trolley wire 1 through the supporting frame and arm 36, contacts 3 and 4, arm 91, block 33 and signal wire 2 to the signal mechanism.

Means are herein provided whereby when the magnet 6 is energized and the armature 5 is attracted the contacts 3 and 4 will be maintained in contact with each other for a predetermined extent of time thus ensuring that the signal circuit 2 will be closed long enough to effect the setting of the signal.

The armature-carrying arm 36 is acted on by a spring 39 which tends to retract said arm and said arm has also connected thereto a retarding device arranged so that it will retard the movement of the arm in both directions. Said arm 36 has a movement considerably greater than necessary to bring the contact 4 into engagement with the contact 3 so that when the magnet 6 is energized the initial movement of the arm 36 will bring the contact 4 against the con-

tact 3 and then the arm 36 will have a further movement into the position shown in Fig. 12 and during this movement the arm 91 will be swung forwardly against the action of the spring 35. As soon as the circuit for the magnet 6 is opened then the arms 91 and 36 will swing back to the position shown in Fig. 2 through the action of the springs 35 and 39. The retarding device referred to operates to retard the movement of the arm 36 in both directions thereby prolonging the time that the contacts 3 and 4 are in engagement even though the magnet 6 is only momentarily energized.

This retarding device comprises a bar 40 carried by a shaft 41 which is formed with a pinion 42 meshing with a gear 43 that is journaled in a bracket or support 44. This gear 43 is connected to the arm 36 by means of a link 45 which is pivoted at one end to a crank pin 46 on the gear 43 and is pivoted at the other end to the end of the arm 36 as shown at 47. When the arm 36 swings from the position shown in Fig. 2 to that shown in Fig. 12 the gear 43 will be given a partial rotation thus rotating the shaft 41 and the arm 40 which acts to retard the motion of the arm 36.

As soon as the magnet 6 is de-energized then the springs return the parts to their initial position and during such return movement the bar 40 acts also as a retarding agent thus causing a slower movement of the arms 91 and 36 than would naturally result from the action of the springs 39 and 35. This device operates, therefore, to maintain the contacts 3 and 4 in engagement for a period of time after the magnet 6 is de-energized thereby giving added time for the operation of the signal.

The magnetically-sensitive element 7 by which the circuit for the magnet 6 is closed is enclosed in a chamber 54 formed in a housing 48 of brass or some non-magnetic material and the housing is secured to a plate 49 of insulating material by means of a suitable screw 50 and it also has associated therewith a plate 51 of brass or other non-magnetic material which is secured to the bridge member or pole piece 15. This pole piece 15 carries a pin 53 of steel which extends through the plate 51 and through the top of the housing 48. This pin 53, therefore, becomes part of the pole piece 15 and has a magnetic attraction for the member 7 so that the member 7 will be suspended therefrom as illustrated diagrammatically in Fig. 5. The magnetically-sensitive element 7 is, therefore, supported by its magnetic attraction to the member 53 and this is sufficient to hold said member 7 suspended from its upper end so that the lower end is free to be swung in different directions.

Since the frame including the pole piece 15 is electrically connected to the trolley wire through the arms 21 it follows that the member 7 will be electrically connected to the trolley wire as indicated in Fig. 5, the electrical connection which is illustrated diagrammatically by the wire connection 9 in Fig. 5 being the supporting frame and the pin 53.

The contact 8 with which the pin 7 operates to close the circuit of the magnet 6 is located at the lower end of the housing 48 and is situated so that swinging movement of the member 7 in one direction will move it into engagement with said contact 8. This contact 8 has a U-shaped form and is constituted by the end of a wire 56 which is supported in a block 55 of insulating material that is situated at the lower end of the housing 48, said block having an opening or recess 97 therein in which the contact 8 is located. The lower end of the magnetically-sensitive member 7 also occupies this opening 97. The contact 8 is connected to the magnet 6 through the following connections. The wire connection 56 extends through the insulating block 55 and the end of said wire connection is bent upwardly against the outside of the insulating plate 49. This insulating plate 49 carries a binding post 58, the latter extending through the plate 49 and one end of said binding post has an arm 57 of conducting material thereon which engages the end of the wire connection 56. This binding post 58 is connected to the magnet 6 through a wire 59. In the diagrammatic view Fig. 5 the electrical connections 59, 58, 57, 56 leading to the contact 8 are indicated diagrammatically at 10 while the electrical connections 105 between the members 7 and the trolley wire including the frame is indicated diagrammatically at 9.

Said magnet is also connected by a wire 11 to a terminal plate 61 which in turn is connected to the ground through a suitable wire connection 12. When, therefore, the magnetically-sensitive element 7 is swung into position to engage the contact 8 then the circuit through the magnet 6 will be closed, said circuit being as follows. From the trolley wire through the shoes 22 and arms 21 and frame of the apparatus including the bridge piece 15, thence through the pin 53 to the contact 7, contact 8, wire 56, arm 57, binding post 58, wire 59, winding of magnet 6, wire 11, terminal 61 and ground wire 12.

As stated above the magnetically-sensitive member 7 normally occupies a position out of contact with the contact 8 and the construction is such that when a trolley harp passes said member 7 the magnetic attraction between the trolley harp and the member 7 will be sufficient to swing the latter 130

into contact with the contact 8 thereby closing the circuit through the magnet 6, which will result in setting the signal as above described.

5 In order to develop the proper magnetic attraction between the trolley harp and the member 7 it is desirable that the trolley harp should be magnetized and while it is within my invention to magnetize said trolley harp 10 in any suitable way yet I have illustrated herein a construction in which the trolley harp is automatically magnetized as it passes the member 7. The trolley harp is of a magnetizable material and it may be magnetized through the operation of the electro-magnet formed by the windings 13 and 14 and the pole pieces 15 and 27. This electro-magnet is situated closely adjacent the path of the trolley harp and when the trolley harp 20 passes into the field of magnetic influence of said electro-magnet said harp will be magnetized and thus as it passes the member 7 it is in a magnetized state so that it has a strong attraction for the member 7 and will 25 draw said member 7 toward it.

The member 7 is guided in its movement by a guide plate 62 which is situated at the lower end of the housing 48 and between the block 55. This guide plate is provided with an opening 68 having the general shape shown in Fig. 14. This opening has one recess 69 in which the lower end of the member 7 is normally received and it has at its opposite side another recess 70 adjacent the contact 8. These recesses are separated by a reentrant pointed portion 71 which functions as a guide or deflector. The lower end of the magnetically-sensitive needle is normally retained toward the side of the opening having the recesses therein through the magnetic attraction of a permanent magnet 72, which is carried by a post 73 secured to the bar 27. The normal position of the magnetically-sensitive element 7 is that illustrated in Figs. 9 and 14, the lower end thereof occupying the recess 69. When a trolley wheel moving along the trolley wire 1 passes the housing 48 in the direction of the arrows Figs. 9 and 1 the magnetic attraction between the trolley harp and the element 7 will draw the element 7 laterally toward the trolley harp thus carrying it out of the recess 69 and as the trolley harp moves along in the direction of the arrow this magnetically-sensitive element is carried in said direction over and beyond the projection 71. When the trolley harp passes so far away from the element 7 as not to magnetically affect the latter then the lower end of the element 7 will be drawn toward the permanent magnet 72 and will then come into the pocket 70 and thus engage the contact 8 thus closing the circuit of the magnet 6.

It will be understood, of course, that the magnetic attraction of the magnet 72 on the

magnetically-sensitive element 7 is less than that of the passing trolley harp so that the presence of the trolley harp swings the member 7 from the position shown in Fig. 9 to that shown in Fig. 14 notwithstanding the continued magnetic attraction of the permanent magnet 72. When there is no trolley harp in the vicinity of the member 7, however, it is controlled by the magnet 72 which holds it in one or the other of the pockets 69, 70.

I have also herein provided means whereby when the magnet 6 is energized and the contacts 3 and 4 are closed such movement will automatically restore the element 7 from the position in which it was left by the passing trolley harp into its normal position shown in Figs. 9 and 14. This is accomplished by means of a restoring member 74 pivoted at 75 to a bracket 76 extending from the housing 48. Said restoring member 74 has a curved arm 77 which operates in a slot 78 formed in one wall of the housing 48. The restoring member is normally retained in its inoperative position shown in Figs. 9 and 10 by means of a spring 79 and when in such position it rests against the part 80 of the bracket 44. The tail 81 of the member 74 is, however, situated in the path of the movement of the lower end of the lever 36 so that when the magnet 6 is energized and the lever 36 is moved forwardly the lower end will engage the tail 81 and swing the member 74 into the dotted line position Fig. 11 thereby causing the curved arm 77 to act on the member 7 and carry the latter out of the pocket 70 and over the point 71 and into the pocket 69.

This mechanism, therefore, provides means for automatically restoring the magnetically-sensitive element 7 into its normal position as soon as the magnet 6 has been energized by the shifting of said member into engagement with the contact 8.

In the construction herein shown the chamber 54 is open at the bottom and I have provided a movable closure therefor in the form of a swinging gate 81 which is pivoted at 82 to an arm 83 extending from the housing 48. When the gate is in the dotted line position Fig. 9 it closes the open end of the chamber 54 and thus prevents the entrance of dirt thereinto.

If it is desired to gain access to the member 7 then the gate may be swung into the full line position Fig. 9 thus opening the lower end of the chamber. Said gate is provided with a thumb piece 84 by which it may be operated.

If desired I may support a mirror 85 on the post 73 beneath the lower open end of the housing so that when the gate 81 is opened it will be easy to observe the operation of the needle 7.

In practice the operating mechanism will

be enclosed in a suitable housing 86 shown in dotted lines in Fig. 4 and in Fig. 3 thereby to give protection to the moving parts.

While I have illustrated herein a selected embodiment of my invention I do not wish to be limited to the constructional features shown as various changes in the construction of the device may be made without departing from the invention.

10 I claim:

1. In a device of the class described, the combination with a magnet and a normally-open circuit therefor, of a circuit-closing device in the circuit comprising a magnetically-sensitive member responsive to the magnetic attraction exerted on it by a passing body, and an electromagnet for holding said member in suspended position, said member when so attracted operating to close the circuit.
- 15 2. In a device of the class described, the combination with an electromagnet having a pole piece, of an actuating magnet, a normally-open circuit therefor, circuit-closing means in said circuit comprising a magnetically-sensitive member suspended from said pole piece and responsive to the magnetic attraction of a passing body, and when so attracted operating to close the circuit.
- 20 3. In a device of the class described, the combination with an electromagnet having a pole piece, of an actuating magnet and a circuit therefor, circuit-closing means in said circuit comprising a magnetically-sensitive needle magnetically suspended from said pole piece and responsive to the magnetic attraction of a passing trolley harp.
- 25 4. In a device of the class described, the combination with a magnet and a circuit therefor, of circuit-closing means in said circuit and comprising two normally-separated contacts, one of which is magnetically sensitive and is adapted to be moved into engagement with the other by the magnetic attraction of a passing body, and means actuated by said magnet to restore said contacts to their separated position.
- 30 5. In a device of the class described, the combination with a magnet and a circuit therefor, of a trolley-controlled circuit-closing device comprising two normally-separated contacts, one of which is magnetically sensitive and is adapted to be moved into engagement with the other by the magnetic attraction of a passing trolley harp, a piv-
- 35 6. In a device of the class described, the combination with a trolley wire, an electromagnet having a pole piece, a housing of non-magnetic material secured to the pole piece, a pin of magnetic material engaging the pole piece and extending into the upper end of the housing, a magnetically-sensitive needle within the housing and suspended from said pin, said needle being electrically connected to the trolley wire, and an insulated contact in the lower end of the housing electrically connected to said magnet, said needle being magnetically responsive to a passing trolley harp and magnetically moved thereby into engagement with the fixed contact thereby to close the circuit through the magnet.
- 40 7. In a device of the class described, the combination with a trolley wire, an electromagnet having a pole piece, a housing of non-magnetic material secured to the pole piece, a pin of magnetic material engaging the pole piece and extending into the upper end of the housing, a magnetically-sensitive needle within the housing and suspended from said pin, said needle being electrically connected to the trolley wire, an insulated contact in the lower end of the housing electrically connected to said magnet, said needle being magnetically responsive to a passing trolley harp and magnetically moved thereby into engagement with the fixed contact thereby to close the circuit through the magnet, and means actuated by the magnet to restore the magnetically-sensitive needle to its normal position.
- 45 8. In a device of the class described, the combination with an actuating magnet, of a pivoted armature therefor, a contact carried by the armature, a pivoted spring-pressed arm carrying a co-operating contact, whereby when the magnet is energized the contacts are brought into engagement and the arm is moved against the action of its spring, and means for retarding the movement of the armature in both directions.

In testimony whereof, I have signed my name to this specification.

JOHN J. RUDDICK.
